UNITED STATES PATENT OFFICE.

CHARLES MARSHALL, OF CAMDEN, NEW JERSEY.

KNOB ATTACHMENT.

SPECIFICATION forming part of Letters Patent No. 473,262, dated April 19, 1892.

Application filed November 25, 1891. Serial No. 413,038. (No model.)

To all whom it may concern:

Be it known that I, CHARLES MARSHALL, a citizen of the United States, residing at Camden, in the county of Camden and State of New Jersey, have invented a new and useful Improvement in Locks, of which the following is a specification.

The object of my invention is to retain the knob of a lock on the spindle thereof without the usual screw which passes through the knob-shank into the knob-spindle.

The invention consists in the combination, in a lock, of a knob-shank provided with a transverse journal-bearing formed in its outer surface, and a longitudinal slot communicating with said journal-bearing and the shank-socket, and a T-shaped connecting-latch composed of a journal, which turns in the bearing of the shank, and a latch bar or end fitted to swing loosely and disengaged in the longitudinal slot and shank-socket or be held in engagement with the rose-plate by the knob-spindle.

On reference to the accompanying sheet of drawings, making part of this specification, Figure 1 is a vertical and transverse section of the door to which the lock is fixed, rose-plates, latch-spindles, and knobs, and the T-shaped connecting-latches which engage the knobs with the rose-plates. Fig. 2 is an inside view of a rose-plate and an end view of the knob-spindle and a connecting-latch. Fig. 3 is a longitudinal and transverse section of the knob-shank, rose-plate, connecting-latch, and knob-spindle of one side, the knob-shank longitudinal slot being shown in heavy black. Fig. 4 is a perspective view of the connecting-latch. Fig. 5 is a perspective view of the end of the knob-shank and connecting-latch; and Fig. 6 is an end view of the knob-shank, showing the connecting-latch swinging loosely or disconnected in its socket, vibrating with its journal.

Similar letters refer to similar parts in the several views.

A is the door; B, the lock latch-spindle, in this instance made square; C D, the rose-plates fixed to the door, and E F the lock-knobs, the shanks *a* of which fit over the ends *b* of the spindle B and extend into the sockets of the rose-plates. Each knob-shank *a* has a transverse journal-bearing *c* formed in its

surface suitably near its end and a longitudinal slot *d*, communicating with said journal-bearing and shank-socket, which extends to the end of the shank. A T-shaped connecting-latch G, composed of a journal H, which turns in the bearing *c*, and a latch extension or end *f*, which is fitted to swing loosely and disengaged in the longitudinal slot *d* and shank-socket *e*, is adapted to engage with the inner side of the rose-plate C, in which position it is held by the knob-spindle B, which fills the knob-shank socket and holds the latch end *f* in contact with the rose-plate in a horizontal position, Fig. 1.

To put my invention in practice, first screw one rose-plate C on the door A and pass the shank *a* of its respective knob E into the rose-plate socket *d*, taking care to have the journal H of the connecting-latch G horizontal and uppermost and its latch end *f* swinging loosely and disengaged in the slot *d* and shank-socket *e*, Figs. 5 and 6. The knob-shank *a*, fitting in the rose-socket *b*, the journal H is restrained from jumping out of its bearing *c*. Next give the knob E and its shank *a* one-half turn, by which the journal H is turned undermost, its latch end *f* dropped into a horizontal position, and its catch engaged with the inner edge of the rose-plate spindle-opening *g*, Fig. 3. The spindle B is subsequently slipped from the opposite side through the door, lock, and rose-plate C into the socket *e* of the knob-shank and above the latch end *f*, which it holds in contact with the rose-plate in every position assumed by the knob, which has a perfectly-free rotary motion. The other knob F can be similarly fixed to the rose-plate D before screwing on the door. The end of the connecting-latch *f* extending beyond the end of the knob-shank *a* and the rose-plate, provision is made for its rotation with its knob and spindle by cutting away the material of the door A, as shown by the angular indenture *h*, Fig. 1.

To remove the knobs E F from the latch-spindle B, turn them until the respective parts assume the relative positions shown in Fig. 1, the connecting-latches *f* uppermost, and unscrew the rose-plates C D. On drawing the rose-plates and knobs from the spindle B the connecting-latches *f* will turn and drop vertically into the knob-sockets, and thereby dis-

connect the parts, for, as shown and described, they are the only means of holding the knobs on the spindle.

I claim—

- 5 The combination, in a lock, of a knob and shank provided with a transverse journal-bearing, and a longitudinal slot communicating with said bearing and the shank-socket, and a T-shaped vibrating connecting latch
10 composed of a journal which turns in said transverse bearing, and a latch end which is

adapted to swing loosely and disengaged in the longitudinal slot and shank-socket or be held in engagement with the lock rose-plate by the knob-spindle for securing the knob on 15 its spindle, substantially as described.

In testimony whereof I affix my signature in presence of two witnesses.

CHARLES MARSHALL.
